ROBERT ABBOTT HADFIELD, OF WESTMINSTER, ENGLAND.

CAP FOR ARMOR-PIERCING PROJECTILES.

1,089,639.

Specification of Letters Patent. Patented Mar. 10, 1914.

Application filed August 22, 1913. Serial No. 786,131.

To all whom it may concern:

Be it known that I, Sir ROBERT ABBOTT HADFIELD, knight, F. R. S., a subject of the King of Great Britain and Ireland, residing at Westminster, England, have invented Improvements in Caps for Armor-Piercing Projectiles, of which the following is a specification.

In caps for armor-piercing projectiles as heretofore employed, it has been usual to make that portion of the cap that surrounds the pointed end portion of the projectile of comparatively large cross sectional area in a plane transverse to the axis of the cap and projectile at the point of the latter, the front end of the cap, which is sometimes made comparatively thin immediately over the point of the projectile, being usually made flat, or convex with a large radius of curvature, or of hollow or cup shape, or of conical shape, the object being to provide a mass of metal that will strike the armor plate to be pierced, over a comparatively large area, and to provide a large mass of metal around the pointed end of the projectile for supporting the same immediately before and just after the projectile reaches the plate. When, however, a projectile fitted with such a cap strikes an armor plate, either normally or obliquely, the cap is liable to be shifted in position relatively to the projectile before the critical moment when the point of the projectile comes in contact with the plate with the result that the projectile is liable to be ineffective.

Now, instead of its being necessary to protect the extreme point of the projectile with such extreme care as has heretofore been usually considered desirable, I have found that while it is desirable to protect the point of the projectile by a thin layer of cap metal arranged to come between it and the face of the plate to be perforated, as heretofore, yet the further massing of such metal around the extreme point is unnecessary. In order that the projectile shall derive the maximum support from the cap it is of importance that the work of expanding or laterally displacing the cap metal should not commence substantially before the critical moment when the point of the projectile meets the face of the plate. With this object in view I have found that the metal of the cap arranged immediately in front of the extreme point of the projectile should be so disposed that it, or most of it, can be displaced and got

rid of or perforated without seriously disturbing the firm setting of the cap on the ogival portion of the projectile or causing it to move relatively to the projectile itself. 60 With existing caps this firmness or solidity of setting is liable to be disturbed and the cap metal to be displaced before the critical moment in question. In the event of such premature disturbance, although a fair result may be obtained, it often happens that the projectile either does not get through the plate at all, or only a portion gets through, owing to its not receiving the maximum support from the cap. 70

Now the present invention has for object to provide caps designed to enable projectiles to perforate hard faced armor in a reliable and effective manner under varying service conditions. To this end, a cap according to the present invention is constructed so that its forward face presents a centrally-arranged portion of comparatively small thickness and cross sectional area to fit over and cover the pointed end of the 80 projectile and with a hollow rearwardly-extending body portion to fit over and surround the ogival portion of the projectile, such body portion having its forward end located behind or below a plane transverse to the axis of the cap and projectile and passing through the point of the latter. The distance that this forward end is located behind the point of the projectile may vary from say one-fiftieth of the caliber of the 90 shell to one-tenth of the caliber of the shell, or any intermediate measurements. The surface of the centrally-arranged forward portion of the cap merges into that of the forward end of the body portion of the cap 95 through an intermediate annular surface of concave or other curved or irregular shape other than a straight shape as seen in a longitudinal section of the cap, so that the front end of the cap is not of conical shape 100 extending gradually backward beyond the front of the projectile but after passing over the front of the projectile, turns outward to form the front end of the rear or body portion of the cap. With such a construction it 105 will be understood that a line drawn as a tangent to the centrally-arranged forward portion and to the body portion of the cap will touch these portions at two points and bridge the intermediate surface of the cap. 110 The central forward portion of the cap is preferably made with a convex surface of

comparatively small radius of curvature and very slightly in front of the point of the projectile, or in some cases it may not be appreciably in front of the extreme point of

5 the projectile at all, and with an annular connecting surface between the said central forward portion and the body portion so arranged as to be substantially behind the point of the projectile to which the cap is 10 fitted.

10 A cap such as described may be provided with a hollow air deflector, mantle or shield of any known or suitable kind which can be attached to the cap or be made integral 15 therewith.

15 In the accompanying drawings, Figure 1 shows partly in elevation and partly in central vertical section and by way of example only, a portion of an armor piercing projectile having a head of say two calibers radius fitted with a cap constructed according to the present invention. Fig. 2 is a similar view to Fig. 1 showing a modified construction.

20 Referring to Fig. 1, *a* is the comparatively thin centrally arranged forward portion of the cap made of a small diameter *a* and with a convex surface of small radius, and *b* is the hollow rearwardly extending body portion of the cap made of comparatively small cross sectional area and with a rounded shoulder at *b*¹, the front surface of the two portions *a* and *b* being merged or connected together by an intermediate annular surface 25 *c* shown as of step-like shape in section, that lies substantially behind the point of the projectile *f*. It will be seen that the forward end *b*² of the body portion *b* of the cap is located well behind a transverse plane 30 *A* passing through the point of the projectile and that the intermediate portion of the cap bounded by the surface *c* is bridged by a line *B* *B* tangent to the central forward and body portions *a* and *b* of the cap 35 and touching the same at the points *X* and *Y*.

40 In Fig. 2 the intermediate surface *c* is of concave shape and the forward end of the body portion *b* extends forward to a greater extent than in Fig. 1, and has a hollow air deflector, mantle or shield *g* of known construction secured thereto to facilitate flight of the projectile as well understood.

45 Upon impact of a projectile fitted with a cap such as hereinbefore described against a hard-faced armor plate the force of the impact will, owing to the small surface area of the central forward portion *a* of the cap, be concentrated over a small surface area 50 of the armor and the said central portion will be compressed, perforated, or turned out of the way, by the point of the projectile *f*, without seriously disturbing the body portion *b* or causing it to commence 55 to expand or move relatively to the pro-

jectile, so that it can offer effective protection to the projectile at the moment required, namely when the point of the projectile reaches the armor.

What I claim is:—

1. A pointed armor piercing projectile and a cap for the forward portion thereof, said cap comprising a relatively thin central portion, formed with a convex surface of small radius of curvature to cover the projectile tip and a relatively thick body extending rearwardly therefrom, the forward end of the body being behind the projectile tip, and the forward surface of the cap being formed with an annular concavity 70 rearwardly of the tip and around said relatively thin, central portion, leaving the tip covered and surrounded only with a relatively thin covering, giving a small point of contact, but a greater thickness of metal in 75 the body and a firm support to the projectile after the tip has penetrated.

2. For an armor piercing projectile, a cap having a centrally arranged forward portion of a small axial thickness to fit over the point of a projectile and a hollow rear or body portion to fit over the ogival portion of the projectile, the front end surface of the body portion having an annular depression therein and joining the outer peripheral 80 surface of the body portion behind a plane transverse to the axis of the projectile and passing through the point of the projectile, the greatest transverse thickness of the cap metal being around the pointed end portion 85 of the projectile but behind the actual point of the projectile, substantially as described.

3. For an armor piercing projectile, a cap having a concave-convex front end surface, the convex surface being centrally arranged and the concave surface extending around the central portion and terminating in a substantially plane annular outer portion located behind the point of the projectile to which the cap is fitted.

4. For an armor piercing projectile, a cap having a centrally arranged forward portion of small axial thickness and cross sectional area to fit over the pointed end portion of a projectile and a hollow rear or body portion to fit over and surround the ogival portion of the projectile, the body portion having its front end surface arranged to come well behind a plane transverse to the axis of the cap and passing through the 115 point of the projectile and the surfaces of the said forward portion and front end of the body portion being joined by an intermediate annular surface that will be bridged by a line drawn tangentially to the said forward and body portions substantially as described.

5. A cap for a pointed armor piercing projectile comprising a relatively thin central portion to cover the projectile tip and 120

a relatively thicker body extending rearwardly therefrom, the forward end of the body being behind the projectile tip, and the forward surface being a single continuous curved surface, the outer edge thereof being behind the projectile tip, and from said outer edge the body extends rearwardly in a rounded shoulder, the total diameter

of the cap increasing and its thickness decreasing toward the rear.

Signed at London, England, this sixth day of August, 1913.
